UNITED STATES PATENT OFFICE.

LONGLEY LEWIS SAGENDORPH, OF CINCINNATI, OHIO, ASSIGNOR OF ONE-HALF TO HARLAN P. LLOYD, OF SAME PLACE.

DESIGN FOR A SIDING FOR BUILDINGS.

SPECIFICATION forming part of Design No. 17,235, dated April 5, 1887.

Application filed December 29, 1886. Serial No. 222,934. Term of patent 14 years

To all whom it may concern:

Be it known that I, LONGLEY LEWIS SAGENDORPH, a citizen of the United States, residing at the city of Cincinnati, in the county 5 of Hamilton and State of Ohio, have invented and produced a new and original Design for Metallic Siding for Buildings, of which the following is a specification, reference being had to the accompanying drawings, forming part 10 thereof.

Figure 1 is a view of a sheet of metallic siding, illustrating my design. Fig. 2 is a section of the sheet shown in Fig. 1, taken at the line *x x*. Fig. 3 is a section of the sheet shown 15 in Fig. 1, taken at the line *y y*.

The surface of the sheet forming the siding is marked by a number of depressed grooves, A and C. The grooves A are long continuous grooves parallel to each other and extend-

ing in a horizontal direction. The grooves C 20 are short grooves, which extend from one groove A to the next, and in adjoining rows alternate with each other. In cross-section the grooves A and C are both semicircular, as shown in Figs. 2 and 3. The general effect of 25 the design is to represent raised brick-work with intermediate curved depressed grooves.

What I claim as new, and desire to secure by Letters Patent, is—

In a design for metallic siding for buildings, 30 the representation of raised brick-work with intermediate depressed grooves, A and C, curved in cross-section, substantially as shown and described.

LONGLEY LEWIS SAGENDORPH.
